UNITED STATES PATENT OFFICE.

LOREN W. PENNEY, OF NEWTON, MASSACHUSETTS, ASSIGNOR TO SACO-LOWELL SHOPS,
OF BOSTON, MASSACHUSETTS, A CORPORATION OF MASSACHUSETTS.

MEANS FOR CLEANING CARDS.

1,307,452.

Specification of Letters Patent. Patented June 24, 1919.

Application filed November 30, 1917. Serial No. 204,593.

To all whom it may concern:

Be it known that I, LOREN W. PENNEY, of Newton, in the county of Middlesex and State of Massachusetts, a citizen of the 5 United States, have invented a new and useful Improvement in Means for Cleaning Cards, of which the following is a specification.

The object of my invention is to provide a 10 simple and effective means for stripping the cylinder or doffer of a carding engine. Heretofore attempts have been made to strip the card of its collected fibers, etc. by means such as a rotary brush which is applied by hand to the card, by a small vacuum nozzle traveling transverse of the machine in close relation to the card so as to draw the fibers, etc., out by suction, by a device similar in construction by which the fibers are blown 15 from the card by a strong air blast and then are carried away by suction, or by a stripping brush which is itself stripped by a second rotary stripper which is cleaned by suction, etc. These devices are all of them more 20 or less successful, but none of them is entirely so.

My invention consists in a cylindrical cleaning brush which may be rotated by power and which may be supported on the 25 carding engine between the cylinder and the doffer so that it may be adjusted to clean either at will. It is supported in close relation to a nozzle connected by a pipe with a vacuum pump or exhaust fan so that the 30 indraft of air from the nozzle will draw the fibers from the teeth of the cleaning brush which are shaped so as not to become clogged.

My invention will be understood by reference to the drawings where it is shown in its 35 preferred form;

Figure 1 being a side elevation of mechanism embodying my invention, the end of the driving shaft of the cleaning brush being in section.

Fig. 2 is a corresponding view showing a portion of the doffer, the cleaning brush and the vacuum pipe in section;

Fig. 3 being a vertical section taken 40 through the cleaning brush on line 3-3 of

Fig. 1.

Only one side of the carding engine is shown and only so much thereof as is necessary to explain my invention.

55 A is a cylinder which is inclosed in a cas-

ing A¹ of the usual character and in the usual way, and carries the wire card clothing a. B indicates the doffer which is also inclosed in its usual portion B¹ of the casing. To the casing A¹ on each side of the engine is pivotally attached at c an arm C which has at its outer end bearings C¹ in which is mounted the shaft C² carrying the stripper C³. These arms C are slotted as at c¹ and within the slot in each arm is an eccentric d mounted on a shaft D which extends across the machine and is hung in brackets D¹ (of which only one is shown) and which are adjustably mounted on opposite sides of the casing A¹, being held thereto by a bolt d¹. These eccentrics d being fast to the shaft D, the turning of the shaft by the handle D⁴ carries the rocking arms C together with the stripper C³ from the position in Fig. 2 where the stripper 70 engages the doffer B, into a position to engage the cylinder A. At the end of the shaft C² is mounted a pulley C⁴ by means of which and a suitable belt, power is applied to the shaft C² to rotate the stripper 75 C³. The shaft D also carries a disk D² having notches d² located at proper points thereon so that the shaft D may be locked to hold the cleaning brush either in contact with the doffer or with the cylinder or in a neutral position, these notches being engaged 80 by a lever D³ having a detent d³ thereon adapted to engage either one of these notches as required. This lever is pivoted to the bracket D at d⁴.

E is a pipe carrying a nozzle E¹ which extends across the carding engine, its length corresponding with the width of the stripper its opening being of a suitable width to secure an effective indraft. To the end of this nozzle is attached a cover e which projects therefrom covering part of the upper surface of the stripper and extending toward the cylinder sufficiently far nearly to engage the periphery of the cylinder when 95 the stripper is thrown over to clean the cylinder. E² is a damper by which the pipe E may be closed and E³ is a hinged door closing a hand-hole in the nozzle E¹ and serving to receive waste to be thrown in by hand.

The nozzle E¹ is mounted on the rocking or swinging carrier or frame which supports the stripping roll C³ so that said nozzle will move with said stripping roll when the latter is moved into engagement either 100 105 110

with the doffer or the carding cylinder, and the casing or cover *e* is of such form as to permit the teeth of the said stripping roll to engage the carding cylinder as well as the doffer.

The stripper *C*³ has a covering of card clothing somewhat similar in character to that of the cylinder and the doffer, but comprising wire teeth which are very much

- 10 longer than those of the cylinder and doffer and of somewhat different shape, and this card clothing is arranged upon the stripper roll to which it is attached so that the ends of its teeth are substantially radial to the 15 axis of the brush comprising said teeth or wires. It will thus be seen that anything which is carried by these wires, when it reaches the nozzle *E*¹ may easily be withdrawn from the brush by the indraft and 20 carried up through the pipe.

The operation of this device will be easily understood. The lever *D*³ is lifted to withdraw the detent *d*³ from the notch *d*² in which it is resting and the handle of the 25 shaft *D* is turned so as to turn the eccentric *d* which throws the arm *C* toward either rotary member, the doffer or the cylinder, as the case may be, after which the lever *D*³ is depressed to lock the shaft *D*. If the stripper 30 engages the doffer, as shown in Fig. 2, it being rotated in the direction of the arrow (see Fig. 2), strips the doffer carrying the fiber, dirt, etc., around until it comes in front of the nozzle when the inward draft draws 35 off from the straight or radial ends of the teeth of the stripper the material collected there, the damper *E*² of course being open at this time. If it is desired to strip the cylinder, the shaft *D* is turned, thus turning the 40 eccentric *d* so as to throw the arm *C* to the right (see Fig. 2) and cause the stripper to engage the clothing *a* on the cylinder *A* when the same operation takes place, the cylinder being cleaned and the collection from it being 45 carried around by the stripper to the nozzle *E*¹ and withdrawn from the teeth of the brush by the vacuum. When the engine has been entirely cleaned the shaft *D* is unlocked and turned so as to turn the eccentric 50 *d* to bring the brush into neutral position where it is locked by the engagement of the projection *d*³ with its appropriate notch *d*².

It is desirable to support the rear end of the nozzle upon a rest *e*¹ mounted on top of the casing *B*¹ and extending the length of the nozzle, *i. e.*, the width of the casing, to present the nozzle at a proper angle to the stripper.

In practice it is also desirable that the 60 stripper shall be rotated at a speed considerably faster than the cylinder, say three times or more as fast. With such speed centrifugal force will act to assist in the removal of the dirt and fly from the stripper especially in view of the shape of the teeth

of the stripper, the outer ends *c*³ of which, it will be noted, are shown as straight, *i. e.*, approximately radial to the axis of the stripper. These ends pick up the dirt and fly from the card or the doffer which when 70 they reach the nozzle, being held on these radial portions of the teeth, are drawn off by the exhaust without obstruction, being held near the periphery of the stripper by centrifugal force.

In using the term "rotary member" I mean any rotary member such as the cylinder or doffer which acts directly upon the material upon which the machine is working.

The pipe *E* connects with a vacuum pump or exhaust fan located in any convenient place, the dirt and fly being taken care of in any convenient manner.

Other embodiments of this invention will 85 occur to those skilled in the art, for I do not mean to limit my invention to the construction shown.

What I claim as my invention is:

1. In a carding engine, the combination 90 with a carding cylinder and a doffer, of a rocking or swinging carrier pivotally mounted on the engine, a rotating stripping roll supported by said swinging carrier, an exhaust nozzle movable with said carrier 95 and extending closely adjacent to said stripping roll, means for changing the working position of said swinging carrier to cause said stripping roll to engage either said carding cylinder or said doffer, and means 100 for locking said swinging carrier in any desired position.

2. In a carding engine, the combination with a carding cylinder and a doffer, of a rocking or swinging carrier pivotally 105 mounted on the engine, a rotating stripping roll supported by said swinging carrier, an exhaust nozzle movable with said carrier and extending closely adjacent to said stripping roll, means for changing the working 110 position of said swinging carrier to cause said stripping roll to engage either said carding cylinder or said doffer, and means for locking said swinging carrier in any desired position, said swinging carrier comprising arms having slots, eccentrics working in said slots and a manually operable shaft carrying said eccentrics.

3. In a carding engine, the combination 120 with a carding cylinder and a doffer, of a rocking or swinging carrier pivotally mounted on the engine; a rotating stripping roll supported by said swinging carrier, an exhaust nozzle movable with said carrier and extending closely adjacent to said stripping 125 roll, means for changing the working position of said swinging carrier to cause said stripping roll to engage either said carding cylinder or said doffer, and means for locking said swinging carrier in any desired po- 130

sition, said stripping roll having substantially radial wire teeth much longer than the teeth of the cylinder and doffer.

4. In a machine of the kind described, a
- 5 rotary member carrying card clothing and a rotary stripper also carrying clothing, and means for supporting said stripper whereby it may be moved into and out of operative engagement with said rotary member, said
- 10 means comprising a rockable arm and means for rocking said arm, said means comprising in said slot in said arm, an eccentric mounted in said slot, and means for turning said eccentric.

- 15 5. In a machine of the kind described, a

rotary member carrying card clothing and a rotary stripper also carrying clothing, and means for supporting said stripper whereby it may be moved into and out of operative engagement with said rotary member, said means comprising a rockable arm and means for rocking said arm, said latter means comprising a slot in said arm, an eccentric mounted in said slot, means for turning said eccentric, and means for locking 20 said eccentric whereby the position of said stripper may be locked with relation to said rotary member. 25

LOREN W. PENNEY.
